(57) **CLAIM**

The ornamental design for pin striped thin film solar module for garden lamp, as shown and described.

DESCRIPTION

FIG. 1 is a perspective view of a pin striped thin film solar module for garden lamp showing our new design.

FIG. 2 is a front side elevational view thereof.

FIG. 3 is a left side elevational view thereof.

FIG. 4 is a right side elevational view thereof; and,

FIG. 5 is a top plan view thereof.
